UNITED STATES PATENT OFFICE.

WEBSTER THOMAS, OF OXFORD, OHIO.

MACHINE FOR TENONING SPOKES.

Specification of Letters Patent No. 22,903, dated February 8, 1859.

To all whom it may concern:

Be it known that I, WEBSTER THOMAS, of Oxford township, in the county of Butler and State of Ohio, have invented a new and 5 useful Improvement in Machines for Tenoning Spokes for Wagons, Buggies, and other Vehicles; and I do hereby declare that the following is a full, clear, and exact description of the same, reference being had to 10 the annexed drawing, forming part of this specification, in the several figures of which similar characters of reference denote the same part.

Figure 1 is a top view of the machine. 15 Fig. 2 is a side elevation, one of the uprights removed. Fig. 3 is a head elevation. Fig. 4 is a side view with elevated bed inserted.

The nature of my invention consists in a 20 peculiar combination of devices hereinafter to be set forth.

The several parts of this machine are supported by a base piece and an upright frame F.

Within frame F is the cutter bearer F' 25 moved vertically on rods P by means of rack R fixed to the cutter bearer, pinion W, shaft S and lever L. This bearer F' carries two series of cutters d and e; the former for cutting curved shoulders and the latter for 30 square shoulders.

Beneath the cutter d is the bed I resting

upon the fulcrum piece f, so as to possess the power of rocking, and thus adjusting itself to the inclination of the lower edge of the spoke for cutting the shoulder to the desired dish of wheel. There is on this bed a 35 screw J to give the requisite length of tenon.

T is the support of the point of the spoke, whose elevation is regulated by the wedge V to the required dish of wheel.

a and b are eccentrics serving as guides for the side of the spoke B''.

The bed B is attached and regulated in 40 inclination by support T and wedge V. The cutters e e operate in connection with this bed for cutting the square shoulder after the tenon has been formed by the lower cutters d d.

Having described my invention and the 50 operation thereof I claim—

The combination of the beds I and B constructed as described, with support piece T, wedge V and the double series of cutters d e in the same cutter bearer; the construction and operation being as described.

In testimony whereof, I have hereunto signed my name before two subscribing witnesses.

WEBSTER THOMAS.
